BASKET COVER

Lewis O. Rast, Swansea, S. C.

Application February 13, 1936, Serial No. 63,775

3 Claims. (Cl. 217—124)

My invention relates to covers for baskets, adapted for holding fruit, vegetables, or the like.

An important object of the invention is to provide a basket cover which is extremely strong, 5 while being light and inexpensive to manufacture.

Other objects and advantages of the invention will be apparent during the course of the following description.

In the accompanying drawing forming a part 10 of this application and in which like numerals are employed to designate like parts throughout the same,

Figure 1 is a perspective view of a basket cover embodying my invention showing the same placed 15 upon the basket,

Figure 2 is a plan view of the same,

Figure 3 is a transverse section taken on line 3—3 of Figure 2,

Figure 4 is an exploded perspective view of the 20 cover, and,

Figure 5 is an enlarged fragmentary plan view of the cover, at one end of the locking strips.

In the drawing, wherein for the purpose of 25 illustration is shown a preferred embodiment of my invention, the numeral 10 designates a basket, for receiving vegetables, fruit or the like. This basket may be of any well known or preferred type.

My improved basket cover is designated, as a 30 whole, by the numeral 11 and comprises a preferably wooden hoop 12. Arranged above this wooden hoop are superposed pairs of strips 13, crossing each other, and extending diametrically of the hoop 12. The strips in the pairs are preferably formed of wood and are preferably longitudinally curved with their convex sides disposed uppermost, whereby the cover is spherically curved with its convex side arranged uppermost. The cover further comprises a lower locking strip

40 14 arranged above the hoop 12 and beneath all of the pairs of strips 13, and an upper locking strip 15 arranged above all of the pairs of strips and extending longitudinally of the lower locking strip and substantially coinciding therewith.

45 The strips 14 and 15 are also longitudinally curved with their convex sides uppermost and are preferably formed of wood. The several pairs of strips 13, and the upper and lower locking strips, are all connected at their inner portions by nails 50 16 or the like. The numeral 17 designates a binding wire hoop, and this binding wire hoop is arranged above all of the pairs of strips 13 and the upper locking strip 15, and is of substantially the same diameter as the hoop 12 and substantially coincides therewith. The binding wire

5 hoop 17 has its material bent or crimped at spaced intervals, affording short locking portions 18, which extend generally radially of the binding wire hoop and are disposed between circumferentially extending portions 19. The binding wire hoop is connected with the wooden hoop 12 by staples 20, which straddle the short locking portions 18 and these staples pass through the ends of the strips 13, 14, and 15 and enter the wooden hoop 12, to attach the strips to the wooden hoop. 10 It is thus seen that the binding wire hoop 17, the several strips, and the wooden hoop are all securely held together by the staples, and the binding wire hoop reinforces and strengthens the 15 cover. The wire hoop cannot slip circumferentially with respect to the wooden hoop, since the staples 20 straddle the short locking portions. The binding wire hoop obviously opposes the distortion of the cover. Further, the generally radial or laterally extending locking portions 18, 20 permit of the staples having their closed ends arranged circumferentially of the hoop 12, so that the legs of the staples will enter the hoop 12, in or adjacent to the central circumferential line of the hoop, thereby preventing splitting of the 25 hoop.

I prefer to form the binding hoop or strip 17 of wire, but I also contemplate forming the same of other material such as sheet metal, wood, 30 fabricated material or the like.

In the use of the cover, it is applied to the upper open end of the basket 10 and the wooden hoop 12 is mounted upon the upper end of the basket and receives such upper end therein. The ends of the locking strips 14 and 15 extend radially beyond the cover proper, so that they may engage handles 21 or other suitable means, serving to hold the cover in the closed position upon the basket. 35

It is to be understood that the form of my invention herewith shown and described is to be taken as a preferred example of the same and that various changes in the shape, size, and arrangement of parts may be resorted to without departing from the spirit of my invention or the 40 scope of the subjoined claims.

Having thus described my invention, what I 45 claim is:

1. A basket cover comprising a hoop, strips arranged above the hoop and adjacent thereto, a binding wire hoop arranged above the strips and adjacent to the first named hoop, the binding wire hoop having generally radial locking portions, and staples receiving therein the generally radial locking portions and having their closed 50 55

ends extending substantially circumferentially of the hoop and driven through the strips and into the first named hoop.

2. A basket cover comprising a hoop, strips arranged above the hoop and adjacent thereto, a binding wire hoop arranged above the strips and adjacent to the first named hoop and having substantially the same diameter as the first named hoop, said binding wire hoop having spaced generally radial short locking portions, and staples having their closed ends extending substantially circumferentially of the hoop and receiving the short locking portions therein and driven through the strips and into the first named hoop.

3. A basket cover comprising a hoop, a cover structure arranged above the hoop, staples securing the cover structure to the hoop and having their closed ends extending circumferentially of the hoop and their legs driven into the hoop adjacent to the central circumferential line of the hoop, and a binding hoop arranged above the cover structure and extending circumferentially of the cover hoop and having generally radial locking portions which are passed through the closed ends of the staples. 5 10 15
